US00D953332S

(12) **United States Design Patent** (10) **Patent No.:** **US D953,332 S**
(45) **Date of Patent:** **** May 31, 2022**

(54) **MULTIFUNCTION ADAPTER**

(71) Applicant: **GUANGDONG GOPOD GROUP HOLDING CO., LTD**, Shenzhen (CN)

(72) Inventor: **Zhuowen Liao**, Shenzhen (CN)

(73) Assignee: **Guangdong Gopod Group Holding Co., Ltd.**, Shenzhen (CN)

(**) Term: **15 Years**

(21) Appl. No.: **29/726,939**

(22) Filed: **Mar. 6, 2020**

(30) **Foreign Application Priority Data**

Oct. 30, 2019 (CN) 201930594823.5

(51) **LOC (13) Cl.** **14-99**

(52) **U.S. Cl.**

USPC **D14/433**

(58) **Field of Classification Search**

USPC ... D14/432, 433, 434, 435, 435.1, 436, 439, D14/480.1–480.7, 484.1, 203.1–203.8, D14/240, 242; D13/107, 108 CPC G06F 13/122; G06F 13/382; G06F 13/385; G06F 13/4022; G06F 13/4282; G06F 1/1632; G06F 1/1684; H01R 25/006; H05K 5/0278; G06K 19/07732

(57) **CLAIM**

The ornamental design for a “multifunction adapter”, as shown and described.

DESCRIPTION

FIG. 1 is a front perspective view of a multifunction adapter; FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures depict portions of the multifunction adapter that form no part of the claimed design.

1 Claim, 8 Drawing Sheets
